UNITED STATES PATENT OFFICE

MATTHEW S. OGONOWSKI, OF UTICA, NEW YORK

CENTRIFUGAL CLOTHES DRIER FOR WASHING MACHINES

Application filed January 20, 1930. Serial No. 422,178.

This invention relates to centrifugal clothes driers for washing machines, and an object of the invention is to provide a means for introducing water during the drying operation, so as to eliminate the removal of the clothing from the drying compartment for rinsing the clothes.

Another feature of the present invention is to provide for equal distribution of the rinse water thru all of the clothing in the drying compartment, and to furthermore provide for aerating the clothing during the rinsing operation by utilizing the vacuum or suction created by withdrawing the rinse water.

Another feature of the invention is to provide for causing the clothes to be equally divided in the drying compartment, thereby reducing vibration of the drier to a minimum.

With the foregoing and other objects in view, the invention consists of a novel construction, combination and arrangement of parts as will be hereinafter more specifically described and illustrated in the accompanying drawings, wherein is disclosed an embodiment of the invention, but it is to be understood that changes, variations, and modifications, may be resorted to without departing from the spirit of the claim hereto appended.

In the drawings, wherein like reference characters denote corresponding parts throughout the several views:—

Figure 1 is a fragmentary section vertical in detail through a portion of a washing machine illustrating the improved centrifugal clothes drier assembled therewith,

Fig. 2 is a fragmentary, top plan view thereof.

Fig. 3 is a horizontal section taken substantially on the line 3—3 of Fig. 1, and looking in the direction of the arrows.

Referring to the drawings in detail, 4 indicates an offset portion of a conventional washing machine that is adapted to be equipped with the centrifugal drier in accordance with the present invention.

Numeral 5 indicates the top wall of the washer and 6 indicates the bottom wall of the container. Rising from the bottom wall 17 of

thereof. Formed between the top and bottom wall of the washer 4 is a circular compartment or container 7 formed by a vertically disposed circular wall 8 that is secured in any conventional manner to the top and bottom walls. The drying compartment 7 is open at its top and is closed by a hinged cover 9. The cover 9 is stationary and removably supported on the top wall 5 by means of turn buckle 10 mounted on the top wall 5, the inner ends of which are adapted to overhang the flange 11 about the perimeter of the cover 9.

A depending apertured collar 12 is formed in the center of the bottom wall 13 of compartment 7 to form a bearing for the drive shaft 14 that extends therethrough. The drive shaft may be connected with any suitable driving mechanism not shown in the drawings.

The rotatable drying chamber indicated generally at 15 consists of a vertically disposed, hollow, cylindrical container in the form of a basket 16, open at its top and having its bottom wall 17 resting on a disk 18 secured to the inner end of drive shaft 14 by a nut 19 that threadably engages about the inner end of said drive shaft.

In the center of the bottom wall 17 is a socket 20 which is counter-sunk with respect thereto in which the nut 19 is seated. Bottom wall 17 is imperforate, but the side wall is formed with vertically spaced, staggered openings 21. The openings 21 are coextensive with the side walls. A cover 22 for drying chamber 15 is formed with a beveled flange 23 depending from its outer periphery that rests upon the upper rolled edge 24 of the chamber.

The cover 22 is adapted, in a manner to be presently described, to rotate with the drying chamber 15. The cover 22 is spaced below the cover 9, the bottom wall 17 of container 16 is spaced from the bottom wall of compartment 7, and the side walls of the chamber 15 are spaced from the walls 8 of compartment 7.

Furthermore, container 16 is disposed concentric with respect to the walls of the

drying chamber 15 is a tubular member 25 that extends vertically through the axis of the chamber and is substantially co-extensive therewith.

5 In the embodiment shown in the drawings, the bottom of the tubular member 25 is formed integral with the bottom wall 17, but it is within the contemplation of the invention to secure the bottom of the tubular member to the bottom wall 17 in any conventional manner. The bottom of the tubular member 25 is closed, by the wall 26 and is open at its top.

10 The side wall of the tubular member 25 is formed with staggered openings 27 throughout its entire length and the number of openings formed in the guide walls progressively increase from the bottom to the top thereof. The tubular member 25 is materially less in diameter than the container 16, and this tubular member 25 terminates slightly below the upper edge of the drying chamber.

15 A bearing housing 29 is secured by means of screws 30 to the outer face of the stationary cover 9 at the center thereof. Depending from the center of the bearing plate is an open conductor pipe 31 that provides an inlet into the tubular member 25 and is to receive the discharge end of a hose not shown in the drawings. The top of the housing is provided with a central opening communicating with the pipe 31.

20 Supported in a pocket 32 formed in the side wall of the bearing housing 29 is a stationary, vertically disposed ball race 33. The stationary cover plate 9 and the cover 22 that rotates with the drying chamber 15, are formed with registering openings, and the opening 34 in cover 9 is larger than the openings in cover 22.

25 Extending through these openings in covers 9 and 22 is a sleeve 35 threaded on its outer face, adjacent the upper and lower ends thereof. The inner face of the sleeve 35 is spaced from the conductor pipe 31 which extends through its axis. A nut 36 threadably engages with the threaded upper portion of sleeve 35 and rigidly secures a rotating ball race 37 disposed about a plain portion of the sleeve. The lower end of the ball race 37 bears on the upper end of a tubular collar 38 that is disposed about the sleeve 35, and the lower end of this collar rests upon the upper face of cover 22 about the opening therein.

30 The collar 38 is disposed in spaced relation to the walls of the openings 34, so that it will not rub the walls of the opening, when it rotates with the sleeve 35. A tubular nut 39 threadably engages the threaded lower portion of sleeve 35 and has depending, inwardly flared portion 40 that is received in the upper end of the tubular member 25.

35 Ball bearings 41 are disposed between ball races 37 and 33 to form a bearing between

the stationary cover 9 and the rotating cover 22. From the foregoing description, it will be apparent that the axial disposition of tubular member 25 prevents clothes from being fed into the rotating drying chamber 15 in an uneven manner, but requires the clothes to be clearly packed about this tubular member, all of which goes to require even distribution of the weight of the clothes to eliminate vibration and the moving parts.

40 The progressive increase in the number of openings from the bottom to the top of tubular member 25, provides an equal flow of water throughout the entire length of the tube, the increase in number of openings compensating for the increased pressure at the bottom of the tube, due to the weight of the column of water therein.

45 When the clothes are packed in drying compartment 15, a hose introduced into conductor pipe 31 will introduce water from a remote source, either hot or cold, as the drying compartment 15 is rotated. The flow of water through tubular member 25 and the openings 21 in chamber 15, provides for a continuous rinsing of the clothes and the drying thereof in a single operation.

50 When the clothes in the chamber 15 have become rinsed properly the influent water may be cut off. A suitable drain conductor 41 connected through the bottom wall 13 of chamber 7 leads to any conventional type of pump not shown in the drawings, to carry off rinse water that collects in the bottom of compartment 7. As the rinse water is pumped out of compartment 7, the air that displaced the water will aerate the clothing in chamber 15.

55 It is to be understood that by describing in detail herein a particular form, structure or arrangement, it is not intended to limit the invention beyond the terms of the claim, or the requirements of the prior art.

60 Having thus described my invention, what I claim as new is:—

65 A centrifugal clothes drier for washing machines comprising a fixed open top container, a perforated open top basket mounted for rotation in the container, an upstanding, perforated tube fixed centrally in the basket and having an open upper end adjacent the top of the basket, a stationary cover for the container having a centrally disposed opening therein, an upstanding housing mounted on the cover having a central opening in its top disposed coaxially with the cover opening, a stationary tube formed integrally with the housing and depending therefrom through the cover opening in spaced, concentric relation thereto, a rotatable tube encircling the stationary tube and extending through the cover opening in spaced, concentric relation thereto into the housing and having externally threaded upper and lower portions, a collar mounted on an intermediate

portion of the rotatable tube, a bearing mounted in the housing and encircling the rotatable tube and engaged with the collar, a nut threaded on the upper portion of the 5 rotatable tube and engaged with the bearing and, in conjunction with the collar, constituting means for connecting the rotatable tube with the bearing, said bearing constituting means for rotatably mounting the rotatable 10 tube on the cover, a basket cover mounted on the rotatable tube and engaged on the basket for rotation therewith, said basket cover being engaged with the collar, and a nut threaded on the lower portion of the rotatable tube 15 and engaged with the basket cover, said nut having a tapered extension depending below the rotatable tube and engageable with the upper end of the perforated tube.

20 In testimony whereof I affix my signature.
MATTHEW S. OGONOWSKI.
